UNITED STATES PATENT OFFICE.

JOHN B. HADAWAY, OF SWAMPSMOTT, MASSACHUSETTS, ASSIGNOR TO UNITED SHOE MACHINERY COMPANY, OF PATERSON, NEW JERSEY, A CORPORATION OF NEW JERSEY.

ROTARY TACK-PULLING TOOL.

1,028,455.

Specification of Letters Patent.

Patented June 4, 1912.

Application filed February 23, 1910. Serial No. 545,286.

To all whom it may concern:

Be it known that I, JOHN B. HADAWAY, a citizen of the United States, residing at Swampscott, in the county of Essex and 5 State of Massachusetts, have invented certain new and useful Improvements in Rotary Tack-Pulling Tools; and I do hereby declare the following to be a full, clear, and exact description of the invention, such 10 as will enable others skilled in the art to which it appertains to make and use the same.

The invention relates to tack pulling machines in which the tacks are acted upon 15 and extracted by one or more tack pulling blades arranged at the periphery of a rotary tack pulling tool or wheel.

In lasting a welt shoe a number of lasting tacks are driven along the sides of the shoe 20 to hold the upper in place upon the last, and a wire is usually passed along the toe and secured at each end by an anchor tack. After the shoe upper has set, the side tacks are removed and a few stay tacks are driven 25 to hold the upper in position on the last during the sewing operation, the anchor tacks and toe wire remaining on the shoe. After the inseam has been sown it is necessary to remove the stay and anchor tacks prepara- 30 tory to performing the subsequent operations upon the shoe. The heads of these tacks are often flush with or below the inner edge of the welt, so that it is difficult to remove them without injury to the inseam.

35 The primary object of the present invention is to provide a tack pulling tool which may be utilized to pull the anchor and stay tacks from the shoe, and which will operate to pull such tacks in an efficient and reliable manner without danger of digging into the upper or welt in such manner as to injure or weaken the inseam.

To this end one feature of the invention 45 contemplates the provision in a machine for pulling tacks, of a rotary tool provided with guard flanges which project beyond the working edge of the tack pulling blade or blades so as to protect the inseam from injury when the tacks are presented in position to be engaged and extracted by the 50 blades. With this construction the work may be held against the guard flanges in bringing the tack into the path of the working edge of the blade without bringing the 55 upper or inseam into the path of the work-

ing edges of the blades, since this path lies within the peripheries of the guard flanges. The tack pulling blades will therefore engage and extract any tacks, the heads of which may project slightly above the edge 60 of the welt, without danger of injury to the inseam. In case the head of the tack is flush with or below the inner edge of the welt, then the head of the tack may be brought into the path of the tack pulling 65 blades by pressing the work against the guards with sufficient force to cause the inseam to spring inward between the guard flanges, and thus the tack may be extracted with little danger of digging into the welt, 70 and upper sufficiently to injure the inseam.

In the preferred construction of the invention, danger of injury to the inseam in pulling tacks, the heads of which are below the inner edge of the welt, is further 75 reduced or eliminated by providing a guard flange intermediate the side flanges, the periphery of which lies slightly within the path of travel of the working edge of the tack pulling blade. With this construction the 80 side flanges may be separated so that the operator may readily spring or bend the inseam inward between the flanges, and at the same time the intermediate flange will limit the extent to which the tack pulling blades 85 may dig into the welt or upper, and will thus prevent injury or weakening of the inseam.

A further feature of the invention contemplates the provision in a tack pulling machine provided with a rotary tack pulling tool, of an improved construction and arrangement of the tack pulling blades which enables the blades to be readily removed for sharpening, and to be readily 90 adjusted to maintain their working edges in proper relation to the guard flange or flanges.

The invention also includes certain other features of construction and combinations 95 which are hereinafter described and referred to in the claims.

The features of the invention will be readily understood from an inspection of the accompanying drawings and the following detailed description of the tack pulling machine illustrated therein.

In the drawings Figure 1 is an elevation of a tack pulling machine provided with a tool embodying the invention in its pre- 110

ferred form; Fig. 2 is a sectional view on line 2—2, Fig. 1; and Fig. 3 is an elevation of the tack pulling tool showing the manner in which it operates in pulling the tacks.

5 In the construction shown in the drawings the spindle 1 of the tack pulling machine carries on its outer end a tack pulling tool 2 which is especially adapted for engaging and extracting the sole tacks from a lasted shoe. The spindle also carries a second tack pulling tool which is especially adapted for pulling the stay and anchor tacks, and which embodies the present invention. This tool comprises the guard flanges 3, 4 and 5, and the tack pulling blades 6, which are secured in the hub 7 on which the guard flanges are formed. The 10 tack pulling blades 6, of which there are four in the construction shown, are arranged between the side flanges and the intermediate flange 5 in the manner shown in Figs. 2 and 3. These blades are provided with convex working edges which are so arranged with relation to the side flanges 3 and 4 that the peripheries of the side flanges extend somewhat beyond the path of the working edges of the blades. The intermediate flange 5 is somewhat smaller in diameter than the side flanges 3 and 4, and lies 15 slightly within the path of the working edges of the blades 6.

In utilizing the tool for extracting stay or anchor tacks from a shoe, the shoe is

35 preferably presented to the tool with the line of tacks extending at right angles to the axis of the wheel, the line of tacks being fed to the wheel by the operator by movement of the shoe in line with the direction of travel of the tool, as indicated in Fig. 3.

40 When the shoe is thus presented to the tool, the side flanges 3 and 4 engage the welt and the upper or insole, and tend to hold the work so that it does not intersect the path of travel of the working edges of the blades.

45 In case a tack is below the inner edge of the welt, or is somewhat embedded in the work, the inseam may be forced up between the flanges 3 and 4 to bring the tack into the path of the blades. When the work is thus

50 forced inward between the flanges 3 and 4, the flange 5 limits the digging in of the blades 6 so that they cannot dig into the upper or welt sufficiently to injure or weaken the inseam.

55 In order that the blades 6 may be readily removed for sharpening, and may be readily adjusted radially to maintain their working edges in proper relation to the guard flanges, these blades are adjustably mounted in 60 sockets 8 formed in the hub 7 between the flanges 3, 4 and 5. As shown these sockets consist of cylindrical holes passing through the hub 7 and screw threaded at their inner ends to receive adjusting screws 9. The 65 blades 6 are provided with cylindrical

shanks 10 fitting within the sockets 8 and supported at their inner ends upon the screws 9. The shanks of the blades are held from rotation within the sockets by means of screws 11, the inner ends of which engage flattened surfaces formed on the shanks 10. The outer surfaces of the blades 6 are curved to provide clearance back of the working edges of the blades, and as the blades are ground or worn away they should be adjusted radially outward to maintain the working edges in their proper position with relation to the guard flanges. This may be readily accomplished by adjustment of the screws 9. By loosening the screws 11 the 70 blades may be readily removed and replaced, for the purpose of sharpening or repairs.

The invention has been described with relation to its application to a tool especially 85 designed for pulling stay and anchor tacks, but it will be understood that the invention is not confined in its application to the pulling of stay or anchor tacks, but may be employed, if desired, in pulling lasting or side 90 tacks. It will also be understood that the features relating to the manner of mounting and adjusting the tack pulling blades may be embodied with advantage in tack pulling tools which are designed for pulling either 95 lasting or sole tacks, as well as in tools designed for pulling stay or anchor tacks.

While it is preferred to employ the specific construction and arrangement of parts shown and described, it will be understood 100 that this construction and arrangement is not essential except so far as may be set forth in the claims, and may be varied and modified without departing therefrom.

Having explained the nature and object 105 of the invention, and specifically described one form of tack pulling tool in which it may be embodied, what I claim is:

1. A rotary tack pulling tool provided with one or more tack pulling blades, and 110 guard flanges projecting beyond their working edges between which the inseam is fed longitudinally, substantially as described.

2. A rotary tack pulling tool provided with tack pulling blades, guard flanges on 115 opposite sides of the blades projecting beyond their working edges between which the inseam is fed longitudinally, and an intermediate flange to press on the inseam beyond which the working edges of the blades 120 project, substantially as described.

3. A rotary tack pulling tool provided with side flanges and an intermediate flange of less diameter than the side flanges, tack 125 pulling blades between the side and intermediate flanges, the working edges of which are within the peripheries of the side flanges and beyond the periphery of the intermediate flange, substantially as described.

4. A device for pulling stay tacks com- 130

prising a tack pulling blade arranged to act on the line of the inseam, a guard along which the inseam is fed longitudinally, arranged to guide the inseam out of the path 5 of the blade while allowing the operator to bring the inseam into the path of the blade, substantially as described.

5. A device for pulling stay tacks comprising a guard between which the inseam is

fed longitudinally and a guard arranged to 10 act on the line of the inseam between said guards and a tack puller operating in the line of the inseam between the former guards, substantially as described.

JOHN B. HADAWAY.
